ATTORNEY.

UNITED STATES PATENT OFFICE.

BENJAMIN F. FORTINER, OF CAMDEN, NEW JERSEY, ASSIGNOR TO THE HALE AND KILBURN MANUFACTURING COMPANY, A CORPORATION OF PENNSYLVANIA.

CAR-SEAT FRAME.

SPECIFICATION forming part of Letters Patent No. 782,841, dated February 21, 1905.

Application filed November 18, 1904. Serial No. 233,353.

To all whom it may concern:

Be it known that I, BENJAMIN F. FORTINER, of Camden, county of Camden, State of New Jersey, have invented an Improvement in Car-
5 Seat Frames, of which the following is a specification.

This invention relates to the means for securing the outer upholstery or covering to the base of the main box-frame of car-seat cushions or backs, and is particularly adapted for
10 fireproof constructions in which the main box-frame is formed of sheet metal.

It is the object of the invention to effect a neat and secure fastening of the edges of the
15 covering without the use of rivets, bolts, eyelets, or kindred devices, which are liable to tear and otherwise injure the covering.

In the drawings, Figure 1 is an inverted plan view of a car-seat frame embodying my
20 invention with a portion of the springs and slats broken away to show the interior. Fig. 2 is a cross-section of the same on the line A A of Fig. 1. Fig. 3 is a cross-sectional view in perspective of part of the seat-frame,
25 showing the clamping device before it is closed down or clamped; and Fig. 4 is a similar view showing the clamping device closed down.

The details of construction of the frame
30 structure outside of the clamping devices form no part of the present invention and may be varied to suit the ideas of the constructor.

As shown, the body of the structure consists
35 of a rectangular sheet-metal frame *a*, of substantially L-shape in cross-section, having top and bottom flanges *a'* *a''*, which may be curved or beaded at the edges, as at *a'*. The longest sides of the box-frame have their upper outer
40 surfaces depressed, as at *a*³, to receive the ends of the transverse flat springs *b* and the rivets *b'*. These springs are preferably provided upon their under faces with a central strip *b*² of increased strength. Coiled springs
45 *d* are bolted at their upper ends to the strips *b* *b'*, and their lower ends are supported by transverse stamped sheet-metal slats *e*, the ends of which are provided with feet *e'*, resting on the inner surface of the lower flanges *a''*.

Above the spring-plates *b* is placed the up-
50 holstery or covering, which usually consists of a sheet of canvas *c* and a covering of outer material *c*, such as woven ratan. This up-holstery or covering may be fireproofed.

The covering is pulled down over the box-
55 frame and folded over the beaded portion *a'* with the edges extending more or less over the inner face of the flange *a''*, as shown at *c'*. The clamping-strip *n*³ is then applied. This clamping-strip has a longitudinal flat 60 portion *n*³ and a hooked or curled edge *n'*, terminating in a clamping-jaw *n*². When first applied, this edge *n'* is slightly upturned or open, so that it may be hooked over the flange *a'* and the edge of the covering *c* with 65 the flat portion *n*³ resting on the covering below the flange, as shown in Fig. 3. The hooked portion *n'* is then compressed or clamped down and the jaw *n*² is forced down upon the projecting edge *c'* of the upholstery 70 and clamps it upon the flange *a''* inside of the bead *a'*, as shown in Fig. 4. This affords a very strong and efficient fastening for the up-holstery, and as no teeth, rivets, or other means are employed which penetrate the fab- 75 ric there is less liability to tearing.

In the construction shown the clamping-strips on the long sides of the frame are formed with notches or openings *n*⁴ in the curled edge *n'*. These are intended to permit 80 the ends of the slats *e* to extend over the clamping-strip and rest on the bead *a'*. They are therefore unnecessary at the ends, where the hooked portions *n'* are continuous.

The clamps may be made in long strips, as 85 shown, or in short sections.

What I claim as new, and desire to secure by Letters Patent, is as follows:

1. In a car-seat frame, the combination of a box-frame having lower beaded flanges, a 90 covering of upholstery having its edges brought under the lower beaded flanges and over upon the upper surface thereof, and clamps having a lower face resting on the up-holstery under the flanges, and hooked por- 95 tions extending over the beads and clamped down upon the edges of the upholstery on the upper faces of the flanges.

2. In a car-seat frame, the combination of a box-frame having lower beaded flanges, a covering of upholstery having its edges brought under the lower beaded flanges and over upon the upper surface thereof, and clamps resting on the upholstery under the flanges and having hooked portions extending over the beaded edges of the flanges and provided with a clamping-jaw n^2 clamped down upon the edge of the upholstery on the upper face of the flanges said hooked portions being provided with notches or openings n^4 , and transverse slats having their ends extending through said notches or openings and resting at their extremities on the opposite lower flanges of the box-frame.

3. In a car-seat frame, the combination of a box-frame having lower beaded flanges, a covering of upholstery having its edges brought under the lower beaded flanges and over upon the upper surface thereof, and clamps consisting of longitudinal strips rest-

ing on the upholstery under the flanges and having hooked portions extending over the beaded edges of the flanges and provided with a clamping-jaw n^2 clamped down upon the edge of the upholstery on the upper face of the flanges said hooked portions being provided with notches or openings n^4 , and transverse slats having their ends extending through said notches or openings and resting at their extremities on the opposite lower flanges of the box-frame.

In testimony of which invention I hereunto set my hand.

BENJAMIN F. FORTINER.
